[57] ABSTRACT

A device for evaluating the difference between two inputs. The first input is applied to a counter and the second is applied to a memory device. A pulse generator then pulses the counter and a storage device until the count in the counter corresponds to the second input signal in the storage device. At this point the pulse generator is stopped. The count in the storage is therefore indicative of the difference between the first and second inputs since it received a pulse for each pulse required to raise the value of the input of the counter to the value of the input of the memory device.

FIG.

FIG.3

FIG.4

FIG.5

DEVICE FOR EVALUATING THE DIFFERENCE BETWEEN TWO VARIABLE INPUTS

FIELD OF THE INVENTION

The present invention relates to a device for evaluating the difference between two inputs of variable magnitude.

DESCRIPTION OF THE PRIOR ART

Electromechanical devices for counting the duration of such communications have been used, generally incorporating rotary switching elements or uniselectors. Such devices are usually heavy, bulky and slow.

SUMMARY OF THE INVENTION

The device of the present comprises a counter connected to receive a first input; a memory connected to receive a second input; drive circuitry operable after the first and second inputs are received to progressively step a counter so that it approaches the state of the memory; a storage device connected to the drive circuitry to store a value instantaneously significant of the change in value of the counter; coincidence circuitry connected to detect coincidence of the counter value and memory value; and output circuitry for noting the stored value when the coincidence circuitry indicates such coincidence.

The counter and the memory each consists of an array of bistable devices, the number of devices in each array being the same. The storage device may comprise a further array of bistable devices.

The drive circuitry comprises a pulse generator which supplies the counter and storage device with pulses which are synchronously counted by the counter and storage device until coincidence between the counter and memory are indicated.

The device further comprises an auxiliary memory connected to receive a third input, the drive circuitry being initially operable after the first, second, and third inputs are received to progressively and synchronously change the states of the counter and memory so that the state of the memory approaches the state of the auxiliary memory. The device includes auxiliary coincidence circuitry connected to detect coincidence of the memory and auxiliary memory states, the drive circuitry being adapted to respond to such coincidence between the memory and auxiliary memory by discontinuing the progressive change in the state of the memory. The storage device is adapted to store a value representative of the change in the counter value only after that coincidence between the memory and auxiliary memory states.

This invention may be used for the evaluation of the duration of a telephone or telegraphic communication. In this case, the first and second inputs consist of timing signals provided by a time marker at the beginning and end of the communication. These are recorded in a central memory and subsequently transferred into the counter and memory respectively to initiate the evaluation cycle.

In one embodiment of the invention, the first, second and third inputs of the device consist of three successive states of a time marker. The first and second inputs mark the beginning and end of the communication, and the third marks the time at which the first and second

inputs are transferred to the counter and memory respectively. The first and second inputs are temporarily held in a central memory, being transferred therefrom to the counter and memory at the same time as the third input is transferred directly to an auxiliary memory. This reduces the amount of space required in the central memory, because only a portion of the timer state providing the second input is transferred into the central memory.

10 The invention will now be described, by way of examples only, with reference to the accompanying diagrammatic drawings in which:

BRIEF DESCRIPTION OF THE DRAWINGS

15 FIG. 1 is a simplified block diagram of a preferred embodiment of the invention.

FIG. 2 is a simplified block diagram of a modified preferred embodiment of the invention.

20 FIGS. 3 and 4 are diagrams illustrating the operation of the devices shown in FIGS. 1 and 2 respectively; and

FIG. 5 is a diagram further illustrating the operation of the device of FIG. 2.

DESCRIPTION OF THE PREFERRED EMBODIMENT

The devices which are described are used for the calculation of the duration of a telegraphic or telephone communication. It will be appreciated that this is merely one of many possible applications of such devices.

Referring to FIG. 1, a calculator device includes three groups of bistable devices G_1 , G_2 and G_3 . Group G_1 comprises $(N + 1)$ bistable devices BD_0 to BD_N , each connected to receive on a respective input B_0 , over a respective one of a set of lines HD_0 to HD_N , marking signals from a memory M . These signals indicate the state of a time marker at the beginning of a communication. Since a respective output F_1 of each bistable device is connected to inputs E_0 and E_1 of the following bistable device the group G_1 also forms a divider.

Group G_2 comprises $(N + 1)$ bistable devices BF_0 to BF_N . Marker signals indicating the state of the time marker at the end of a communication are received at inputs B_0 over respective wires HF_0 to HF_N .

Group G_3 constitutes a counter C_r made up of bistable devices connected as a divider. It provides reading in decimal code. A line R_2 resets the counter C_r to zero.

50 A line CB is linked to inputs B_1 of all the bistable devices of groups G_1 and G_2 . The connection is made through a respective diode and resistance, as will be explained fully below.

An astable multivibrator GR is connected to drive groups G_1 and G_3 simultaneously, and receives a start signal over a line D , under the control of an amplifier L . This start signal acts on a resistance RD connected between the negative pole of a direct current supply and a point X on line D .

60 With amplifier L it is also possible to interpret control signals provided by comparators C_0 to C_N each having two inputs E_1 and E_2 which are respectively connected to outputs S_0 of the bistable devices having the same number in groups G_1 and G_2 . In other words, input E_1 of comparator C_n is connected to output S_0 of bistable device BD_n and input E_2 is connected to output S_0 of bistable device BF_n , and so on. The outputs S_0 of

these comparators are connected through the respective diodes dc_0 to dc_N to a common point Y. A resistance RL is connected between point Y and the negative pole of the direct current supply previously referred to.

With each bistable device of group G_1 is associated a pair of resistances RD and RD_a . In each case, one end of resistance RD is connected to the negative pole of the direct current supply, and the other end is connected to the cathode of a respective diode dda whose anode is connected to one end of resistance RD_a . The other side of RD_a is connected to input B_0 of the bistable device in question. These connections allow the bistable devices to be set to state "one" by the application of a negative voltage to their inputs B_0 .

Input B_1 of each bistable device of group G_1 is connected to line CB through a respective resistance Rd and diode ddb . This connection permits the bistable device to be set to its "zero" state by a signal applied to input B_1 over line CB .

The junctions of the diodes dda with their respective resistances RD are connected to line $C1$ over which a positive signal can be applied to inhibit the negative potentials from the direct current source applied to the inputs B_0 of the bistable devices of group G_1 . Each junction is also connected to the cathode of a respective diode dd the anode of which is connected to the respective one of the wires HD_0 to HD_N .

In group G_2 , input B_0 of each bistable device is connected through a respective resistance RF_a and diode dfa and resistance RF to the negative side of the direct current supply. This connection is identical to that of inputs B_0 of the bistable devices of group G_1 , and serves the same purpose, namely to set the bistable devices of group G_2 to "one."

Again as in group G_1 , inputs B_1 of the bistable devices of group G_2 are connected through respective resistances Rf and diodes dfb to line CB . As in group G_1 , this connection serves to set the bistable devices to state "zero."

Again as in group G_1 , the junction of each diode dfa with its resistance RF is connected to line $C1$, and through a respective diode df to the respective one of lines HF_0 to HF_N .

The diodes dc , dd , dda , ddb , df , dfa , and dfb referred to in the description of the input connections to the bistable devices of groups G_1 and G_2 serve simply as de-coupling diodes.

The point X is connected to wire D through a de-coupling diode d_1 , the cathode of which is connected to point X and the anode of which is connected to the line D. The point X is also connected to the cathode of a diode d_2 . The anode of d_2 is connected to the anode of another diode d_3 the cathode of which is connected to point Y. The anodes of diodes d_2 and d_3 are connected to an input b_0 of the amplifier L. Output S_0 of amplifier L is connected to input B_0 of the astable multivibrator GR.

Output S_1 of the multivibrator GR is connected to the anodes of de-coupling diodes d_4 and d_5 . The cathode of diode d_4 is connected to the inputs E_0 and E_1 of bistable device BD_0 of group G_1 . The cathode of diode d_5 is connected to the input of the counter C_r .

In FIG. 2, a greater part of the circuitry is identical to that of FIG. 1, and FIG. 2 has accordingly been sim-

plified. As in FIG. 1, there is a group G_1 of bistable devices BD_0 to BD_N receiving marking signals from a memory M. As in FIG. 1 this group G_1 constitutes a counter group. Group G_2 includes less bistable devices than FIG. 1. It contains $(n + 1)$ bistable devices BF_0 to BF_n , where n is less than N. Group G_3 also receives marking signals from the memory M. Group G_3 is a counter, as in FIG. 1, and has a line RZ for resetting the counter to zero.

The reference numerals in FIG. 2 which are the same as those in FIG. 1 refer to the same elements. In FIG. 2, the de-coupling diodes and resistances of the bistable device input connections have not been shown, to simplify the diagram.

The device of FIG. 2 includes a fourth group of bistable devices G_4 which includes $(N + 1)$ bistable devices BT_0 to BT_N . These receive marking signals from a time marker device MT.

During a first time period, bistable groups G_1 and G_2 are connected to the generator GR through a switching element AE. This is shown schematically as a relay-type change-over contact, but it will be appreciated that this switching function is actually done electronically. In a second time period, the switching element AE switches to connect groups G_1 and G_3 to the generator GR.

An amplifier L_1 , controlled by the outputs of comparators C_0 to C_N starts and stops generator GR.

Further, comparators C_{oa} to C_{na} each have two inputs, one connected to a respective one of the bistable devices BF_0 to BF_n , and the other connected to a respective one of the first $(n + 1)$ bistable devices BT of group G_4 . The outputs of comparators C_{oa} to C_{na} are applied to an input of a second amplifier L_2 the output of which controls the switching element AE.

The operation of the device of FIG. 1 is as follows:

Before it is brought into operation to time a communication, the device is an idle or ready state. From an administration center of the communication network (not shown) a polarization signal is applied to line CB . This signal, in the form of a negative voltage, is applied to inputs B_1 of the bistable devices of groups G_1 and G_2 , all of which bistable devices switch to their state "one." In this state, the bistable device outputs S_1 take up a positive potential and outputs S_0 a negative potential.

For each of the comparators C_0 to C_N , the inputs E_1 and E_2 receive the same negative voltage, from the outputs S_0 of their respective bistable devices. There is no output voltage at outputs S_0 of these comparators, and no voltage appears at point Y.

Accordingly, Diode d_3 is forward biased and amplifier L conducts because of the voltage applied to its input b_0 . The resulting positive output voltage of the amplifier is applied to input B_0 of the multivibrator GR which is therefore blocked.

The administration center also grounds line $C1$, thereby inhibiting inputs B_0 of the bistable devices of groups G_1 and G_2 and preventing premature recording of the marking signals.

This polarization signal applied to wire CB marks the beginning of communication, and the device remains in the state just described until the end of the communication. At this time, the polarization signal on wire CB is suppressed, as is the signal on wire $C1$. For the moment however, the bistable devices rest in state "one." The

line D is grounded by the administration center, so that the point X takes up a positive potential which will subsequently enable the amplifier L to be blocked. This amplifier is not blocked, however, so long as none of the comparators C_0 to C_N provides an output.

At this point, data relating to the beginning and end of the communication is transferred into the device from the memory M, over lines HD_0 to HD_N and lines HF_0 to HF_N . Consequently, certain of the bistable devices of groups G_1 and G_2 switch to state "zero," while others remain in state "one." This depends on the signal applied to the corresponding lines HD or HF .

At the end of this transfer, the data recorded in the device consists of the state of a time marker at the beginning of the communication, which is recorded in bistable devices BD_0 to BD_N , and the state of this same marker at the end of the communication, recorded in bistable devices BF_0 to BF_N .

Since the data recorded in each of the groups G_1 and G_2 is not the same, some of the comparators c_0 to c_N provide a positive output voltage at their output S_0 . Point Y is thus driven to a positive potential which blocks amplifier L and consequently allows the multivibrator GR to begin generating pulses. The output S_1 of the multivibrator is applied simultaneously to the bistable devices of group G_1 and the counter C_r , constituting group G_3 .

Groups G_1 and G_3 thus begin to count the pulses from multivibrator GR, but group G_2 remains in its initial state. This state corresponds to the time marker position at the end of the communication.

The counting in groups G_1 and G_3 continues until the states of the bistable devices of group G_1 are identical to the states of the corresponding bistable devices of group G_2 . The count made in this time corresponds to the duration of the communication.

This process is shown symbolically in FIG. 3. In section *a* of FIG. 3, the three lines G_1 , G_2 and G_3 show the states of the corresponding bistable groups immediately after the transfer of information from memory M into the device.

Group G_1 records a value indicated PD representing the time at the beginning of the communication. Group G_2 records a value PF corresponding to the end of the communication. Group G_3 is initially at zero.

As shown in section *b*, groups G_1 and G_3 then count simultaneously, as indicated by the arrows, until the state of group G_1 coincides with that of group G_2 . The count is then stopped, as will be described in detail below, and it is clearly seen from FIG. 3 that the state of group G_3 is then indicative of the duration of the call, being equal to the difference between the values PF and PD .

The count is stopped by stopping counter groups G_1 and G_3 . This is carried out by comparators C_0 to C_N . When the states of groups G_1 and G_2 coincide, none of the comparators provides a positive output. The positive voltage at point Y is thus removed, to unblock amplifier L and in turn block the multivibrator GR. Groups G_1 and G_3 receive no further pulses from the multivibrator GR. G_1 and G_3 therefore stop, retaining their corresponding values.

The operation of the device shown in FIG. 2 is as follows:

This device allows only part of the marking of the end time of communication to be recorded in the memory, so as to provide, in the memory, a greater number of levels for recording informations other than those concerned in the calculation of the time duration of the communication.

As in the device of FIG. 1, while in its ready state, the device receives a polarization signal on line CB which sets all bistable devices to state "one." This includes the bistable devices of group G_4 .

At the end of the communication, the data from the memory M is transferred into the bistable devices of group G_1 over lines HD_0 to HD_N , signifying the time of the start of the communication, and into bistable devices BF_0 to BF_N , over lines HF_0 to HF_N , corresponding to the timer state at the end of communication. At the same time, the timer state at the moment of transfer is applied to the bistable devices of group G_4 , over lines HT_0 to HT_N .

The states taken by the groups G_1 to G_4 immediately after this transfer are symbolized in section *a* of FIG. 4, corresponding to section *a* of FIG. 3. Groups G_1 and G_2 record values PD and PF respectively, representing the start and end of the communications. Group G_4 holds a value PT significant of the moment of transfer. Group G_3 is initially zero.

It is seen from FIG. 4 that the time interval $PD-PT$ is slightly greater than the interval $PD-PF$. The interval $PF-PT$, that is to say the period elapsed between the end of the communication and the moment of transfer, can vary slightly, depending on the availability of the appropriate circuitry of the administration center, the point PT being displaced further towards the right as the waiting period for transfer increases.

The number of timer steps, which is a measure of the corresponding time interval between the end of communication and the moment of transfer, makes it possible to determine the minimum number n of bistable devices required for group G_2 , in order that the latter may record the n marking signals signifying the time at the end of the communication. The memory M itself withdraws the data from n first bistable devices of the time marker MT . This process is shown symbolically in FIG. 5. In FIG. 5 are shown the time marker MT , with its $(n+1)$ bistable devices, the memory M, and the calculator device CD which is that shown in FIG. 2.

The time marker MT takes up successive states signifying the progress of time during the communication. At the beginning of a communication the states of its bistable devices are recorded in a corresponding $(n+1)$ divisions of the memory M. This part of the memory is labeled HD in FIG. 5.

At the end of communication, the states of the first $(n+1)$ bistable devices of the marker MT are transferred into $(n+1)$ divisions of memory M, indicated at HF . At the moment of transfer, the values stored in sections HD and HF of memory M are simultaneously transferred into groups G_1 and G_2 respectively of the device DC. At the same time, the states of all $N+1$ bistable devices of the time marker MT are transferred into group G_4 of the device CD.

After this transfer, the generator GR is started by amplifier L_1 and during a first time period, indicated in section *b* of FIG. 4, provokes the simultaneous advance of groups G_1 and G_2 , selected by the switching element

A.E. The progress or count continues until the state of group G_2 coincides with the state of that part of group G_4 formed by its first $(n+1)$ bistable devices.

This coincidence is detected and signalled by the comparators C_{0a} to C_{na} , which unblock amplifier L_2 which applies a control signal to the switching element AE which responds by opening the connection between the generator GR and group G_2 .

During this first time period, group G_2 advances from its initial position PF to an intermediate position PF1, coinciding with position PT of group G_4 . During this time, group G_1 passes from position PD to position PD1. In this way, a shift is obtained in both the start position marked on group G_1 and the end position marked on G_2 , without any modification of the interval between them.

Moreover, the position PF1 now coinciding with position PT, it is possible to calculate the duration of the communication by evaluating the interval PD1-PF1.

In order to do this, groups G_1 and G_3 are connected during a further time interval by the switching element AE to the generator GR. This switching of group G_3 occurs simultaneously with the separation of group G_2 from the generator. The generator GR brings group G_1 to a state identical to that of group G_4 , under the control of the comparators C_0 to C_N which detect the coincidence, applying a signal to amplifier L_1 which blocks the generator GR to stop counting in groups G_1 and G_3 . This part of the operation is shown in section c of FIG. 4.

Group G_1 advances from position PD1 to position PF1, and group G_3 advances by the same amount from its starting zero position. The final position of group G_3 thus gives the total duration of the communication. The duration of the communication may be given directly in decimal code, for example, by direct read-out from decimal dividers connected in cascade and making up the group G_3 , the read-out taking place from the outputs of the bistable devices of this group.

While the device has been described incorporating bistable flip-flop elements, it will be appreciated that any suitable form of device providing an equivalent bistable function may be used instead. Integrated circuits and magnetic toroidal cores may be particularly suitable for certain applications. Obviously if other forms of bistable devices are used, the detailed wiring of the device will be modified to suit the characteristics of the particular elements used.

The device is suitable for applications other than the calculation of a time interval such as the duration of a telephone or telegraphic communication. For example, it may be used to calculate the duration of any time interval, or the difference between other forms of initial and final values than times. For example, it may be used to calculate the difference between the number of articles held in a storage area at any particular time and the number held in the same storage area at a different time. The device is generally applicable to all such cases where the difference between two quantities is to be evaluated.

What we claim is:

1. A device for evaluating the difference between two inputs of variable magnitude, comprising: a counter means for receiving the first input; a memory

means connected to receive the second input; drive means operable after the first and second inputs are received for progressively changing the state of the counter means so that it approaches the state of the memory means; a storage means connected to the drive means to store a value corresponding to the instantaneous increase in the value of the counter means above the first input caused by the drive means; coincidence means connected to detect coincidence of the value of the counter means and the value of the memory means; and output means for noting the value of the storage means when the coincidence means detects a coincidence.

5 2. A device as claimed in claim 1, wherein the counter means and the memory means consist respectively of a first and second array of bistable devices, the number of devices in each array being the same.

10 3. A device as claimed in claim 2, wherein the storage means comprises a third array of bistable devices.

15 4. A device as claimed in claim 1 wherein the drive means comprises a pulse generator for supplying pulses to the counter means and storage means the pulses being counted by the counter means and stored until coincidence of the counter and memory states is indicated.

20 5. A device as claimed in claim 2 wherein the coincidence means comprises an array of comparators each having two inputs, a first input connected to the output of a respective bistable device of the counter means and a second input being connected to the output of a respective bistable device of the memory means.

25 6. A device as claimed in claim 1, further comprising an auxiliary memory means for receiving a third input and wherein the drive means starts operating after the first, second and third inputs are received to progressively and synchronously change the state of the counter means and memory means so that the state of the memory means approaches the state of the auxiliary memory means, the device further including auxiliary coincidence means for detecting coincidence of the memory means and auxiliary memory means, the drive means adapted to respond to such coincidence between the memory means and auxiliary memory means by discontinuing the progressive change in the state of the memory means and the storage means adapted to store the value corresponding to the counter value only after that coincidence between the memory means and auxiliary memory means.

30 7. A device as claimed in claim 6 including a central memory means arranged to simultaneously transfer the first and second inputs to the counter means and memory means respectively and to initiate an evaluation cycle.

35 8. A device as claimed in claim 7, in which the central memory means is arranged to transfer simultaneously the third input to the auxiliary memory means.

40 9. A device as claimed in claim 8, further including a time marker, wherein the first and second inputs are successive states of the time marker.

45 10. A device as claimed in claim 9, wherein the third input is a further state of the time marker, said third state occurring at the moment of transfer of the respective inputs to the memory means, auxiliary memory means and counter means.

11. A device as claimed in claim 10, wherein the second input comprises only a part of the corresponding time marker state.

12. A device as claimed in claim 9, in which the time marker is a timing element whose successive states indicate successive times. 5
